[57] **CLAIM**

The ornamental design for a desk, as shown and described.

DESCRIPTION

FIG. 1 is front perspective view of a desk showing my new design;
 FIG. 2 is a top view thereof;
 FIG. 3 is a rear perspective view thereof;
 FIG. 4 is a rear view thereof;
 FIG. 5 is a front view thereof;
 FIG. 6 is a right side view thereof, the left side being a mirror image thereof;
 FIG. 7 is a front perspective view of a second embodiment of the desk shown in FIG. 1; the opposite side being a mirror image thereof;
 FIG. 8 is a front perspective view of a third embodiment of the desk shown in FIG. 1; the opposite side being a mirror image thereof; and,
 FIG. 9 is a front elevational view of a fourth embodiment of the desk shown in FIG. 1; the top and side of the desk are identical to that shown in FIGS. 2 and 6, respectively. The rear view of the embodiments shown in FIGS. 7-9 is identical to that shown in FIGS. 3 and 4.

FIG. 1

FIG. 2

FIG. 3

FIG. 4

FIG. 5

FIG. 6

FIG. 7

FIG. 8

FIG. 9
